By Ab. L. Tector, Atty.

UNITED STATES PATENT OFFICE.

HENRY W. ALVEY, OF MOORELAND, INDIANA.

SPACING DEVICE FOR WIRE FENCES.

SPECIFICATION forming part of Letters Patent No. 561,642, dated June 9, 1896.

Application filed August 15, 1894. Serial No. 520,423. (No model.)

To all whom it may concern:

Be it known that I, HENRY W. ALVEY, a citizen of the United States, residing at Mooreland, in the county of Henry and State of Indiana, have invented new and useful Improvements in Wire Fences, of which the following is a specification.

My invention relates to a novel spacing device for use in the erection of wire fences, and the object that I have in view is to provide a simple construction by which the line-wires may be spaced apart at the proper intervals from each other, and also to sustain the picket-wire while the same is in the process of application to the line-wires. I attain these objects in the manner and with mechanism shown and described in the accompanying drawings and specification.

Figure 1 represents a span of my improved fence. Fig. 2 is a front view of a spacing and twisting frame. Fig. 3 is an edge view of said frame.

a a a are the horizontal or line wires of my fence secured to posts or uprights, such as are ordinarily used in the building of wire fences.

b, Fig. 1, represents the pickets, which are formed of wire and embracing each line-wire, as seen at *b'*, and shown in this case with the two ends of said picket terminating and being wound or coiled around the upper line-wire, as seen at *b'*.

C, Fig. 2, is a spacing-frame supporting the line-wires while the pickets are being twisted, being provided with a movable tension-bar *c'*, mounted in vertical slots at the upper end of uprights *c* and supported by tension-springs *c'*, located in said slots. Said tension-bar *c'* is provided at its center with a wire-clamp *c*, designed to hold the upper ends of the picket-wire while it is being twisted at all the sections between the line-wires.

In the application of my invention the line-wires are all secured to posts at desired distances from each other and corresponding with gage-plates *c*, which are provided with recesses, within which the line-wires rest while the picket is being secured. When the line-wires are all in place, the frame C is placed against side of line-wires, each engaging with its corresponding gage-plate, next the picket-wire being bent double at its middle and passed from beneath on each side of the line-wires, the two branches extending on opposite sides some distance above the upper line-wire and the extremities of said picket-

wire being secured in clamp *c*, so that the tension-springs will hold it up against the lower line-wire. The next step is the twisting of the pickets at each section or space between line-wires. This is accomplished in 60 this case by inserting between the vertical branches of the picket-wire at the lower space between line-wires, as at *b'*, a twisting-bar, by which this section of the picket is twisted, as seen at *b'*. The bar is then introduced in 65 like manner in next higher section and process repeated until all sections are twisted, as seen at *b'*. At each such operation some of the wire extending above upper line-wire and held by clamp *c* is taken up, and after the 70 upper and last section is twisted the wire yet extending above upper line-wire on each side is separately wound around the latter wire with pliers or otherwise, as seen at *b'*.

It will be seen that in this manner of producing a fence that the pickets may be placed at any distance to suit the purpose, and also when applied it is almost impossible to disturb or move the pickets laterally, so firmly are they locked to the line-wires.

Having fully described my invention, what I claim, and desire to secure by Letters Patent, is—

1. A spacing-frame for applying pickets to line-wires of a fence, provided with a vertically-movable spring-sustained bar, and a picket-clamp carried by said bar, for the purposes described, substantially as set forth.

2. A spacing-frame for applying pickets to the line-wires of a fence, provided with a tension device, and a picket-clamp carried by said tension device, substantially as and for the purposes described.

3. A spacing device for applying pickets to fence-wires, comprising a frame of appropriate dimensions, a series of guides for the reception of line-wires, a vertically-yieldable tension-bar carried by said frame, and a clamp fitted on said tension-bar, substantially as and for the purposes described.

4. A spacing device for applying pickets to fence-wires, comprising a frame, the spaced guides arranged to receive the line-wires, and a spring-sustained bar carrying a picket-clamp, substantially as and for the purposes described.

HENRY W. ALVEY.
